5 Claims. (Cl. 313—274)

This invention relates generally to electric incandescent lamps, and more particularly to lamps having tubular bulbs or envelopes containing an axially extending helically coiled filament.

In order to maintain the filament in the envelope axis it has been the practice to use supports of wire or sheet metal. There are known wire supports each formed from a single length of wire and having one end, or a mid portion thereof, clamped to the filament coil and including one or two circular or spiral turns which extend over at least half the envelope circumference and which abut against the envelope wall. Such wire supports are normally located in planes vertical to the envelope axis but in some cases they tend to tilt from those planes into inclined positions when the lamp is moved, whereby the filament coil becomes distorted. It has been attempted to overcome such tendency to tilt by making the support turns of greater diameter than the inner diameter of the envelope, the said turns being compressed during insertion into the envelope so that they abut against the envelope wall. However, insertion of such supports into the envelopes of relatively long tubular lamps becomes difficult when there are many separate supports and they are clamped tightly to the filament coil and must therefore be inserted into the envelope together with the filament coil. In order to overcome these difficulties of insertion, during which the filament coil may easily be distorted and damaged, it has been proposed to insert the wire supports separately into the envelope and to make that part of the support which holds the filament coil so large that the coil may be inserted subsequently through such holding sections of the support. With this type of support it is not possible to clamp the support tightly to the filament coil.

It is an object of the present invention to provide a novel support structure which will obviate the above mentioned disadvantages.

In accordance with one aspect of the invention, the improved support is made of a single length of wire formed to provide two spaced circular turns or rings which extend over at least half the envelope circumference and abut against the envelope wall, and two straight wire sections which extend toward each other from respective said turns and substantially parallel to the envelope axis, and an intermediate portion between said straight sections and which is clamped to the filament coil. Since the circular turns are maintained in fixed spaced relationship by the straight wire sections, tilting of the support is prevented.

In accordance with a further aspect of the invention, that part of the wire support which is clamped to the filament coil consists of a curved section or loop and two clamping legs on respective sides of the loop, said legs extending from the filament coil to the tube wall. The straight wire sections continuing from the clamping legs are then suitably located along the same longitudinal surface line of the envelope. In case the filament is a simple single helical coil the clamping part of the wire support may encompass a coil turn or the wire itself. In the case of a coiled coil filament a turn of the primary coil is preferably held by the clamping part of the support. In order to assure reliable clamping, the clamping legs

2

of the wire support are preferably curved in an opposite sense to the curvature of the adjoining portions of the loop and in overlapping scissor-like relationship, i.e., in the form of a figure 8.

5 Incandescent lamps in which an addition of iodine to the gas filling prevents blackening of the lamp envelope by vaporized filament particles and which have a very small envelope in proportion to the highly loaded short coiled coil filament, consist of a quartz tube which is sealed at both ends by means of pinch seals having foil portions of lead-in conductors embedded therein and which is evacuated and filled with gas through an exhaust tube attached to the envelope wall. The exhaust tip remaining after sealing off the exhaust tube may be utilized to prevent sliding of the wire support along the envelope. To that end, an offset crimp or fold may be formed in the wire support to engage in the cavity formed by the exhaust tip and thereby prevent displacement of the support along the envelope axis, particularly with the lamp positioned vertically. The said crimp or fold may, of course, also engage any other depression or cavity provided in the envelope wall for that purpose.

For a further understanding of the invention reference is directed to the following detailed description and to 25 the accompanying drawing wherein:

FIG. 1 is a perspective view of a portion of a filament coil and a wire support member in accordance with the invention;

FIG. 2 is a side view, partly in section, of a tubular 30 filament lamp containing the support member shown in FIG. 1; and

FIG. 3 is a cross section of a lamp having a modified form of support.

Referring to FIG. 1 of the drawing, there is shown 35 a coiled coil filament 1 having a straight axis A. The wire support comprises two turns or circular loops 2 and 3 lying in spaced planes which are parallel to each other and perpendicular to the axis A, two straight wire sections 4 and 5 in substantial alignment parallel to the axis A, and an intermediate retroverted link-like clamping portion. The said clamping portion comprises a loop 6 at the end of two curved clamping legs 7 and 8 which are arranged in scissors-like overlapping relation forming a figure 8 so that one turn of the primary coil 40 of the filament 1 is firmly enclosed thereby. When the filament 1 and the wire support are inserted into the lamp envelope the coil axis A lies substantially in the axis of the envelope.

In the lamp shown in FIG. 2 the coiled coil filament 1 45 of tungsten wire has its single coiled ends attached to respective inner lead wires 10 of tungsten. Each lead wire 10 is welded to a molybdenum foil 11 with a thin platinum plate (not shown) interposed therebetween. Each foil 11 is connected to an outer molybdenum lead wire 12. The foils 11 are hermetically sealed in pinch seals 14 at respective ends of the tubular quartz envelope 13. Each of the pinch seals 14 preferably has a cross section in the shape of an I or a double T. The lamp envelope 13 is exhausted and filled with gas through an 50 exhaust tube which is subsequently tipped off to leave the exhaust tip 15. The gas filling may consist of nitrogen at a pressure of 600 mm. Hg and iodine vapor at a partial pressure of 15 mm. Hg. The wire support is like that shown in FIG. 1. The diameter of the support turns or rings 2 and 3, when relaxed, is somewhat greater than the inner diameter of the envelope 13. The wire support, with the coiled coil filament 1 clamped thereby and with the support turns 2 and 3 compressed, may be threaded relatively easily into the rather short envelope 13 without damaging the filament.

By way of specific example, a lamp of the type shown in FIG. 2 may be rated to consume 750 watts on a 220

volt supply. The outer diameter of the envelope 13 is about 14 mm. and the total length of the envelope is 68-69 mm. For lamps having a longer envelope and a proportionately longer filament, several wire supports may be used.

The lamp shown in FIG. 3 is similar to that shown in FIG. 2, including the tubular envelope 13', exhaust tip 15' and coiled coil filament 1'. However, in this case the turn or ring 2' of the wire support is formed with an offset crimp or fold 16 is engaged in the cavity formed by the exhaust tip 15'. It will be evident that in this case the exhaust tip 15' may be offset from the center of the envelope 13' so as to be in alignment with the turn 2' of the wire support member.

By virtue of the crimp 16 engaging the exhaust tip 15', the wire support and the filament coil 1' are retained in position even when the lamp is subjected to shocks while in a vertical position. With this construction it is not necessary that the support member turns be proportioned to abut against the envelope wall under compression; they are preferably formed to a diameter which is somewhat smaller than the inner diameter of the envelope. When the support member, together with the filament, is threaded into the envelope 13', it is only necessary to compress the turn 2' containing the crimp 16 until the said crimp 16 snaps into the exhaust tip 15'.

It will be evident that the crimp or fold 16 may be provided in one of the straight wire sections 4 or 5 of the support member and it may be engaged in any suitable indentation of the envelope other than the exhaust tip 15'.

What we claim as new and desire to secure by Letters Patent of the United States is:

1. In an electric incandescent lamp comprising a tubular envelope having therein a helically coiled filament extending axially of the envelope and supported from the inner envelope wall by a wire support member, said support member comprising a single length of wire formed to provide a pair of circular turns extending over at least half the circumference of the inner envelope wall and

35

40

spaced apart longitudinally of the envelope, straight wire sections extending toward each other from respective said turns longitudinally of the envelope, and an intermediate retroverted link-like part between said straight

5 sections extending laterally thereof and terminating in a loop portion clamped around a local point on a single turn of the filament coil so that said single turn extends through said loop portion of the support and is supported therefrom.

10 2. A lamp as set forth in claim 1 wherein the said intermediate part of the wire support member includes clamping legs extending from said loop to respective said straight wire sections.

15 3. A lamp as set forth in claim 2 wherein said clamping legs are curved in opposite directions and form, together with the said loop, a figure 8 providing a scissor-like effect and tightly enclosing the turn of said filament in said loop.

20 4. A lamp as set forth in claim 1 wherein the inner envelope wall has an indentation therein and the wire support member has a portion thereof outwardly crimped forming a projection engaging in said indentation to prevent displacement of the support member longitudinally of the envelope.

25 5. A lamp as set forth in claim 1 wherein the inner envelope wall has an indentation therein and one of the circular turns of the wire support member has a portion thereof outwardly crimped forming a projection engaging in said indentation to prevent displacement of the support member longitudinally of the envelope.
